UNITED STATES PATENT OFFICE.

ALBERT L. JUHL AND RUFUS R. DARDEN, OF NILES, CALIFORNIA.

SIGNBOARD.

Application filed July 30, 1923. Serial No. 654,610.

To all whom it may concern:

Be it known that we, ALBERT L. JUHL and RUFUS R. DARDEN, citizens of the United States, and residents of Niles, in the 5 county of Alameda and State of California, have invented certain new and useful Improvements in Signboards, of which the following is a specification.

Our invention relates particularly to a 10 display sign board structure adapted to be erected where air currents may play upon it.

It is one object of our invention to provide a structure of the character indicated wherein an element is rotated by the action 15 of air currents, the said element being so designed as to present a plurality of relatively large surfaces suitable for display advertising matter.

It is a further object of the invention to 20 provide a device of the character indicated wherein the display advertising surfaces on said element are so arranged as to permit the letters of a word or a group of words to be arranged thereon in their proper sequence 25 about the perimeter of the element and readable as a whole by one complete revolution of the element.

It is a still further object of the invention to provide a device of the character indicated 30 wherein certain fixed display board surfaces are arranged contiguous to said revolute element and used in conjunction with the operation thereof.

In the drawing:

35 Figure 1 is a front elevation of our improved sign board.

Figure 2 is a plan view of the same.

Referring more particularly to the drawing, 1 indicates a base member fitted with 40 ball bearings 2 and supporting vertically positioned revolute shaft 3.

On shaft 3 is positioned a framework comprising top and bottom members 4 and 5 carrying an enclosing drumlike shell 6.

45 The shell 6 in the present case is formed with six distinct sides, each side having parallel lines running longitudinally thereof and describing a reverse curve in transverse cross section. The joining of the several 50 sides forms a number of pockets 7 facing in the same direction whereby a current of air filling the pockets presented to it will cause the shell to revolve, and the successive presentation of the several pockets to the

air current secures the continuous rotation 55 of the shell.

The upper end of shaft 3 is supported in a socket 8 in the lower edge of a sign board 9, the board 9 extending across the top of the shell 6 and thence forwardly and angularly therefrom as at 10 and 11 and thence downwardly to a point adjacent to the ground as at 12 and 13, the portions 12 and 13 extending therefrom to the ground, the board 11 being carried close up to shell 65 6, and the board 13 being spaced a distance therefrom as at 14.

A current of air blowing from the front will be directed to the shell 6 by the flaring boards 12 and 13. The air will readily 70 escape through opening 14 at one side of the shell and thereby relieve the pressure at that side, the pressure on that side being still further relieved by the curved formation of the shell. On the other side, however, the air currents will fill the pockets 7 in shell 3 keeping it in more or less rapid motion as the wind pressure varies.

If, now, a trade-mark such as "Zerole" 80 is printed on the shell with one letter appearing on each side thereof, the revolving shell will bring the successive letters into view and enable an observer to read the word as a whole. This arrangement obviates the necessity of printing the whole sign 85 on one surface and rendering it visible as a whole, thereby attracting attention and lending interest to the sign. The foregoing is, of course, only suggestive of the many ways in which the revolving sign may be 90 used, either alone or in conjunction with fixed signs arranged thereby.

It is obvious that the shell may be made in an almost infinite variety of shapes and sizes and yet be essentially the same invention as disclosed herein; that is a shell revolute by wind pressure and adapted to carry advertising matter on its outer surface.

100 It is to be understood, therefore, that while we have herein disclosed one specific embodiment of our invention, changes in form, construction and method of operation may be made within the scope of the appended claim.

We claim:

105 A device of the character indicated comprising a support and a shell revolutely

mounted thereon, said shell having its surface formed to present a plurality of wind engaging pockets extending longitudinally thereof and facing uniformly in one direction, said shell being provided with surfaces adapted to carry advertising indicia and sign boards arranged contiguous to

said shell on one side and spaced a distance therefrom on the other side whereby to vary the air pressure on opposite sides 10 of said shell.

RUFUS R. DARREN.
ALBERT L. JUHL.
